(57) **CLAIM**

The ornamental design for a wave mitigation structure as shown and described.

DESCRIPTION

FIG. 1 is a front-top perspective view of the wave mitigation structure of the present invention;

FIG. 2 is a front-bottom perspective view of the wave mitigation structure shown in FIG. 1;

FIG. 3 is a front and rear elevational view of the wave mitigation structure shown in FIG. 1;

FIG. 4 is a left-side and right-side elevational view of the wave mitigation structure shown in FIG. 1;

FIG. 5 is a top view of the wave mitigation structure shown in FIG. 1;

FIG. 6 is a bottom view of the wave mitigation structure shown in FIG. 1;

FIG. 7 is a front-top perspective view of an alternative embodiment of the wave mitigation structure shown in FIG. 1;

FIG. 8 is a front-bottom perspective view of the wave mitigation structure shown in FIG. 7;

FIG. 9 is a front and rear elevational view of the wave mitigation structure shown in FIG. 7;

FIG. 10 is a left-side and right-side elevational view of the wave mitigation structure shown in FIG. 7;

FIG. 11 is a top view of the wave mitigation structure shown in FIG. 7;

FIG. 12 is a bottom view of the wave mitigation structure shown in FIG. 7;

FIG. 13 is a front-top perspective view of an alternative embodiment of the wave mitigation structure of the present invention;

FIG. 14 is a front-bottom perspective view of the wave mitigation structure shown in FIG. 13;

FIG. 15 is a front and rear elevational view of the wave mitigation structure shown in FIG. 13;

FIG. 16 is a left-side and right-side elevational view of the wave mitigation structure shown in FIG. 13;

FIG. 17 is a top view of the wave mitigation structure shown in FIG. 13; and,

FIG. 18 is a bottom view of the wave mitigation structure shown in FIG. 13.

(Continued)

The drawings illustrate a wave mitigation structure, as shown in the drawings. The wave mitigation structure has substantially symmetrical front and rear configurations as depicted in FIGS. 3, 9 and 15, and substantially symmetrical left-side and right-side configurations as depicted in FIGS. 4, 10 and 16. Contour lines are included in the various views which depict surface curvature, flatness and/or other shapes.
